CARBURETOR

Arlington Moore, New York, N. Y., assignor, by
mesne assignments, to Maxmoor Corporation,
New York, N. Y., a corporation of Delaware

Application February 5, 1932, Serial No. 591,040

21 Claims. (Cl. 123—119)

My invention relates to means for metering the fuel and air and forming the charge mixture for internal combustion engines, and to methods thereof.

5 This application is in extension of and covers advances over my prior copending application, such as Serial No. 525,992 filed March 28, 1931 containing subject matter cognate to that claimed herein. As in said application, I introduce the fuel on that side of the air metering throttle nearest to the engine cylinders. Discharge of the fuel into this region of reduced pressure keeps the fuel from striking against the throttle and materially assists in fuel vaporization.

10 The ample pressure reduction thus made available at the fuel jet eliminates need for depending, during fractional load operation, on constricted venturi air-flow to produce fuel flow, and permits the air conduit to be of ample section, adapted to supply maximum air when the throttle is opened, and allowing the engine to develop its full power without interference by air constriction.

15 The pressure reduction about the fuel jet, so located however, increases as the throttle is adjusted towards closed position, while the fuel requirements decrease.

In the form of the invention herein disclosed, as in that of said application Serial No. 525,992, I 20 control the fuel supply to accord with the air supply, notwithstanding that the intake depression inductive effect on the fuel tends, when the air is manually varied, to vary in inverse relation to fuel requirements.

25 This control of the fuel is in part accomplished by maintaining the pressure difference on the fuel less than that in the intake by introducing primary air into the fuel passage at the discharge side of the fuel metering orifice, which air introduction is termed herein as air bleeding, thereby enabling the use of fuel metering orifices having areas larger than would be required to pass the proper fuel in response to the full intake depression, and avoiding excessively small fuel passage areas productive of high coefficients of friction. I also control the fuel flow by variation 30 of the fuel metering orifice area with changes in air passage area together with making compensation for intake depression changes due to speed change. Thus the required fuel is supplied for a given load or speed condition at each throttle position partly by regulation of fuel passage area and partly by regulation of pressure differential effective to produce fuel flow as the speed varies at each throttle position.

At full load operation, when the intake depression is low and the fuel requirements high, I also utilize, as in the invention disclosed in said application 525,992 air flow by venturi effect for augmenting fuel flow, the venturi effect being negligible at fractional load operation. The pressure difference effective for fuel flow is thus augmented by venturi effect at full load operation while the effect of intake depression on fuel flow is substantially reduced by air bleeding effect at fractional load operation.

Bleeding air with the fuel, particularly when, as in the present invention, the fuel is discharged into the region of reduced pressure, also facilitates the atomization and vaporization of the fuel, and facilitates the fuel lifting when the pressure differentials are low.

The carburetor of the present invention also comprises means similar to those disclosed in the above mentioned application for supplying fuel in uniform quantity at engine idling and for supplying additional fuel upon engine acceleration.

An object of the present invention is to provide a device of the character specified which is simple and compact in construction, capable of being produced at low cost, and efficient in operation.

Another object of the invention is to prevent attenuation of the pressure differential on the fuel metering orifice by primary air introduction under load conditions characterized by low depressions so as to obtain adequate fuel under such conditions of engine operation.

Another object of the invention is to effect variation of the fuel metering orifice without development of coefficients of friction causing erratic fuel flow.

Other objects of the invention are to effect metering of the fuel from the air valve without causing back lash, distortion and the like, whereby to obtain precision in metering; to effect uniform metering of fuel at engine idling productive of smooth idling operation; and to improve the operation by preventing the admission of dust and dirt into the air bleed openings.

15 *Influence of air flow on fuel flow*

I utilize the air flow for producing depression, augmenting intake depression when the same is weak, to vary the fuel flow directly with the air flow to such extent as can be done without constricting the air flow, by locating the fuel nozzle 10 in one portion of the angular passageway 12 in the casting 14 on the side of the air metering throttle 16 toward the engine cylinders and preferably at the throat of a venturi 18, the throttle being located in the entrance portion of conduit 12 so that the air is deflected to obviate air stratification at certain throttle positions prior to admixture with the fuel. The air flow through venturi 18 serves to produce depression of useful magnitude at full load for promoting fuel delivery. Venturi 18 also assists the elbow bend in conduit 12 in rendering the air uniform in density.

30 *Fuel blasting and vaporizing*

35 I blast or comminute the fuel by gaseous fluid, such as air preferably supplied at atmospheric pressure and induced by the pressure reduction in the intake, this arrangement being satisfactory for lighter fuels, such as gasoline. The air is discharged through the central tubular nozzle 20 and the fuel supplied therearound through the annular passage 22 between air nozzle 20 and the fuel nozzle 10.

40 The nozzles 10 and 20 are secured within a bore 24 of the casting 14, the casting being provided with a fuel passage 26 terminating at the bore 24. The nozzle 20 has a relatively restricted metering orifice 28 for regulating the quantity of air admitted for effecting the desired atomization of fuel. The nozzle 10 has a relatively long cylindrical end portion 30 projecting beyond the discharge end of the air nozzle 20, the length of said projecting portion exceeding several times the diameter of the nozzle 10. The fuel aerated as hereinafter described and discharged into the passage or chamber 30 is subjected to the comminuting action of the air from nozzle 20, which obtains a high degree of atomization because of the elongated passage 30, without appreciable change in the normal fuel lifting effect available. The fuel is thus subject to an aerating action, air blast, and pressure reduction in the intake for effecting fuel atomization and vaporization so that the fuel rapidly permeates the air entering through opening 32 and forms a homogeneous mixture with the air. The vaporizing effect can be augmented, if so desired by application of heat.

45 50 55 60 65 70 While I have illustrated a carburetor of the up-draft type, the invention is also applicable to carburetors of the down-draft type.

The fuel metering means

75 I locate the float chamber 34 below the casting

14 to which the float chamber bowl is secured. The casting 14 comprises a depending portion 36 extending into the fuel in chamber 34.

The portion 36 is provided with a vertical bore 38 terminating in passage 42 below the air throttle 16. A sleeve 40 having a fuel metering orifice 42 below the fuel level is disposed within the bore 38. Fuel is supplied from bowl 34 past check valve 44 and through lower portion of accelerating well 46 and passage 48 to the fuel metering 10 orifice 42, and, after being metered by valve 50, passes through a vertical passage 52 into passage 26.

The valve 50 having a shape as hereinafter described is adjustable in metering orifice 42 15 and is actuated from the air throttle 16, the valve having a tapered head 54 coacting with the contoured edge of the cam 56 which comprises a vertically disposed plate secured directly to and centrally of the throttle plate 16 within the passage 12.

The valve 50 is maintained in engagement with the edge of cam 56 by a spring 58 interposed between sleeve 40 and abutment 60 on the valve stem.

25 The cam plate 56 is also provided with an ear 62 to which the piston 64 working in well 46 is pivotally connected through stem 66, said stem including a flexible shaft portion 68 so that the plunger or piston 64 can be actuated by the 30 throttle without binding of the parts. The well 46 above piston 64 is vented to atmosphere by opening 70 into the bowl 34 above the fuel level therein.

I so arrange the edge contour 72 of cam 56 35 40 so as to take care of changes in intake depression due to air throttling being substantially inversely related to need for fuel.

I overcome this inversion and obtain fuel flow to accord with air flow by causing the cam-controlled fuel valve 50 to give an opening 42 for 45 each air-throttle opening of a size to pass the needed fuel in response to the depression effective on the fuel orifice which, as will be seen later, I keep less than the depression in the venturi at the fuel nozzle, except at low speed full load operation. I preferably obtain the predetermined openings of the fuel orifice by providing cam 56 for operating fuel valve 50 with an edge contour 72 having a predetermined configuration productive of the proper fuel flow, which will be referred to in further detail hereafter. I take care of the fuel needs changing with engine speeds for each fuel valve position by suitable variation of the pressure differential 55 acting on the fuel, as hereafter described under another heading.

50 55 60 65 While the fuel valve 50 can be arranged to supply fuel for idling, I prefer to handle the idling fuel separately in manner described below, and bring the main fuel valve 50 to a substantially closed position during engine idling, thereby avoiding adjustment of the fuel valve 50 for regulation of idling fuel.

65 *Calibration*

The internal combustion engine, such as employed for example in motor vehicles is controlled by means of the throttle to compensate for load or to vary the speed. At each throttle 70 position the speed varies inversely with the load, the maximum speed becoming greater as the throttle opening increases. The fuel required for operation at minimum speeds varies, in general, directly with the throttle opening. It also varies 75

directly with the speed at each throttle position. For economical operation the mixture ratio is varied as the conditions of operation vary, the mixture being made richer for certain conditions of operation and leaner for other conditions of operation. In my invention I control or adjust, as hereinafter described, the pressure differential range effective for causing fuel flow at the various throttle positions, and then produce for each throttle position through cam 56 the particular fuel passage area individually determined for allowing under the adjusted pressure differential as the speed varies, a fuel flow in suitable ratio to the air supplied.

To determine the contours 12 of a key or cam 56, so as to properly control the opening of fuel valve 50 for any particular type of engine, I operate an engine representative of such type at various fixed throttle openings under various loads productive of various speeds. I then adjust valve 50 for each of the several throttle openings until desirably good operation is obtained under such conditions, and form the cam edge 72 so that, when it is put in place in the apparatus, the test openings of valve 50 are duplicated for the several throttle positions. In this way a predetermined correct opening of fuel valve 50 is obtained to go with each air throttle position.

The typical cam contour formation so obtained as shown at Fig. 8 is substantially continuous, the parts merging into one another, and having the points thereof located to give the fuel passage opening corresponding to the differing conditions for various throttle positions. The part 74 of the cam edge 72 engaging the end 54 of valve 50 during engine idling when the air throttle 12 is substantially closed, may be referred to as substantially neutral, being adapted to hold valve 50 so that practically no fuel is passed. The fuel supply for idling is obtained through a special idling jet 76 hereinafter described and sufficient air for slow engine idling is admitted through the several air bleed apertures, the nozzle 20, and the small balanced idling air holes 78 in the air throttle 16.

The cam part functioning for example at small throttle openings is the part coacting with and determining the opening of valve 50 during very low fractional-load operation at which time fuel through idling orifice 76 is being supplied. This in motor vehicle engines represents the take-out period of merging from idling into power operation, and the movement of fuel passage opening for movement of throttle opening is least.

Another cam part functioning for example at the wider throttle openings increases the fuel valve opening at more rapid rate after the idling orifice 76 ceases supplying any material part of the fuel and the intake depression starts decreasing with throttle opening.

The calibration determination of the cam contour is made with the air bleed 82 open to decrease the pressure difference on the fuel orifice 42 as hereinafter described. The calibration is also made under other conditions of engine operation, such as with the air nozzle 20 and the idling fuel jet 76 in operation to supply air. The calibration being made under such conditions, in actual operation of the engine, proper fuel-to-air ratios may be obtained for maximum torque, maximum horse power and maximum economy, each independent of the other. By making the calibration of the fuel passage areas for certain speeds, such as a low speed at each throttle position, proper fuel for such speeds is insured.

and each fuel passage opening is suitable with the changed pressure difference on the fuel to supply proper fuel at other speeds.

Air bleed to fuel conduit

5

To suitably vary the fuel flow upon speed changes at each throttle position and the corresponding fuel valve position, and to lessen the high depression at the exit side of the fuel valve port 42, the vertical passage 82 is provided for limited communication from a source of air at atmospheric pressure to the fuel conduit at a point 84 immediately beyond the orifice 42 but still below the fuel level. The upper end of the passage 82 terminates in a metering orifice 86 of predetermined size located within the float chamber 34 above the fuel level and receiving air from within the float chamber.

By air bleeding through passage 82 the action of depression is divided to be effective on both air coming in at 86 and on the fuel coming in at 42, or otherwise stated, the pressure differential on the fuel is reduced. The size of the metering orifice 86 will vary with the characteristics of the engine on which the carburetor is employed. For example, in one type of engine, the bleed orifice air jet 86 had a diameter of .059".

The reduction of pressure differences across the fuel gate 42 by the admission of air through the bleed passage 82 enables the use at periods of high intake depression of a fuel passage opening at 42 larger than the small opening that would have to be used to hold the fuel back against the full intake depression, with resulting elimination of the irregularity of flow that would be incidental to use of such smaller opening and greater depression.

The variations in intake depression effective on the fixed air bleed hole 84 give a sufficient corresponding variation in air flow therethrough and in fuel flow through valve port 42, in response to the remaining depression effective to produce fuel flow, to keep the fuel-to-air ratio from going up unduly with increase in engine speed for each air gate and fuel gate position, the air bleeding effect increasing with increase of depression upon increase in speed at each throttle position.

At wide open air-throttle operation, for example, when the fuel gate position at 42 is fixed by fuel valve 50 at the maximum opening, the inductive effects on the fuel of intake depression and air flow vary directly with the speed and so directly with need for fuel, the air bleeding effect then being minimum, and the resultant pressure difference enables the securing through the unchanging fuel passage opening, of the variation of several hundred percent in fuel flow that is required through the speed range in full load operation.

The admission of air at 84 with the metered fuel coming in at 42 produces an air-fuel mixture in the conduit which, on passing to nozzle 12, is more effectively broken up than solid liquid fuel by blasting and/or delivery into partial vacuum. As the fuel has already been metered at 42 prior to admixture with the bleeding air, the correct air-to-fuel proportioning can be obtained.

While the depression available with my process could be used to lift fuel through some distance, I dispense with such function, and supply the fuel close up to the nozzle at a constant float controlled level, to avoid the irregularities in supply of fuel that occur when fuel is lifted through substantial distances.

75

It will be noted that the vertical primary air passage 82 is submerged below the fuel level in the float chamber so that, when the pressure in the intake is atmospheric, fuel will rise in said passage 82 up to the level of the fuel in the float chamber. It follows therefore that, upon engine operation, the reduction in pressure in the intake must attain a value sufficient to draw the fuel out of or dump the passage 82 before the primary air becomes effective in reducing or attenuating the pressure reduction at the metering orifice 42. Should the depression during engine operation, such as at low speeds characterizing engine lugging conditions, fall below that required to dump the passage 82, the latter hydrostatically fills with fuel to automatically close off the introduction of primary air, and thus to render the entire available pressure reduction in the intake or venturi effective in producing fuel flow. The critical value of depression at which the passage 82 dumps the fuel or fills with fuel depends on the extent of submergence of said passage and of the metering orifice 42, the extent of submergence being designed in each case to satisfy the requirements for operation. The hydrostatic control of the primary air as above described provides effective means for tailing up the mixture ratio at low speeds characterizing engine lugging conditions, and thereby reduces the liability of the engine stalling at such low speeds.

At engine idling air passage 82 is open and fuel valve port 42 is substantially closed so that the fuel conduit 52 admits air only, and such air serves as a carrier for the idling fuel mixture supplied at 76 and delivered to the fuel nozzle 10 through the last reach 26 of conduit 52. Furthermore, the depression for supplying idling fuel is materially reduced by the communication 40 through passage 82 to atmosphere being open.

I have found in modulating the fuel flow in some types of engines through a metering orifice employing the well known tapered or conical metering pin, forming an annular orifice, that the fuel flow at certain light engine loads is erratic, the fuel flow tending to lean out or fall off. I have discovered that this decrease in fuel flow is due to frictional coefficients inherent in the use of a variable annular orifice for fuel metering subject to high pressure differences.

When metering fuel with an annular orifice, say at 10° of throttle opening, even when employing air bleeding, the clearance must be of the order of .00125" so as to prevent excessive fuel flow at the high intake depression existing at such throttle position. An annular orifice of such size is so small that light hardly passes through the same. Fuel passing through such highly restricted orifice is therefore subjected to considerable frictional retardation, the action being accumulative and gradually reducing fuel flow. That the disturbing effect of the coefficients of friction is serious with an annular orifice is evidenced by the fact that the fuel flow has been found to vary to a considerable extent in a short period of time. Upon movement of the metering pin the original fuel flow is reestablished but again rapidly falls off as the metering orifice remains fixed. In actual engine operation, the tendency of the fuel to lean out upsets the mixture ratio and causes the pressure differential to vary, which in turn also affects fuel flow, detrimentally disturbing the engine operation.

I overcome the disturbing effects of frictional coefficients by the provision of a variable orifice

42 having a cross-section which is lumped or concentrated, approximating in shape a round hole instead of an annulus so that the wall surface of the orifice frictionally retarding the fuel flow is minimum and the minimum dimension thereof is substantially greater than the minimum dimension of an annular orifice. 5

In order to form the variable lumped orifice 42, the lower end 88 of the valve 50 is made cylindrical with one side thereof cut or slabbed off at an angle, as indicated at 90, to form a frustum. The angle of the plane cut 90 is such as to allow variation in the area of the fuel orifice throughout the relatively small range of movement of the pin 50, and is so coordinated with the cam 15 contour 72 that an orifice of the desired fuel passage area is obtained at each throttle position. 10

In the position of the valve 50 shown in the drawings the completely cylindrical portion of the pin 50 substantially closes the orifice 42 to 20 preclude the passage of fuel therethrough at engine idling. As the valve 50 moves with opening movement of the throttle the fuel passage area at 42 increases, the orifices of increasing area 25 formed being substantially segmental in shape, as indicated at 92, Fig. 12; an orifice of this shape having less fuel flow retarding effect.

The lower valve portion 88 is preferably separate from the upper portion 94, and is preferably loosely received into a socket 96 in portion 94 and 30 movably retained therein by a pin 98. This allows the portion 88 to line up with the orifice 42 should the same be made slightly off center in manufacturing.

The frustum type of metering valve may be 35 more readily manufactured and installed than the conical type of valve, a greater range of tolerance being allowable.

As shown at Fig. 11 the valve 50a may be made with a cut 90a having a predetermined contour 40 or curve, instead of being made plane as indicated at 90, Fig. 10. With this arrangement the pin 50a can be connected to the throttle for movement directly therewith without the use of the interposed cam 56. In such case the cut contour 45 90a is formed to give at each throttle position a segmental metering orifice of the area desired for that throttle position.

The provision of means for varying the fuel passage area 42 in the manner above described 50 in conjunction with air bleeding into the fuel at 86 not only insures steadiness in fuel flow under constant conditions of engine operation but also allows greater precision in air bleed adjustment at 86 for controlling the differential pressure on 55 the orifice 42 for engine load variations, making it possible to obtain a substantial increase in economy.

With my carburetor the mixture ratio can be adjusted or altered at service stations or elsewhere merely by replacement or substitution of the air bleed jet 86 which is removable. For example, with a cam 56 of predetermined contour and a metering valve 50 of a predetermined cut at 90, the mixture ratio for the entire range of 65 engine operation can be made leaner by use of a larger air bleed and richer by use of a smaller air bleed, the correction being made for the entire range of engine operation substantially equally effectively for all stages of engine operation so 70 that it is impossible, although the adjustment is simple, to obtain faulty operation at any stage of engine operation, the adjustment when made being satisfactory for the entire range.

The frustum type of metering valve while en- 75

abling precision in fuel metering also enables production at low cost, and the same, when carburetor cost is a factor can be advantageously utilized for controlling the fuel orifice 42 to supply fuel for engine idling as well as at other stages of engine operation, the relatively low coefficients of frictions characteristic of the lumped type of metering orifice being productive of steadier fuel flow at engine idling. I prefer however, where cost is not material, to utilize for supplying idling fuel the means 76 hereinafter described, because such means is substantially immune to fluctuations in intake depression at engine idling.

15 *Regulation of fuel flow for various engine speeds*

If the engine speed is increased with the air metering throttle wide open, the air flow increases rapidly, necessitating a correspondingly considerable increase in fuel supply. A typical case is increase from 100 cc. per min. at substantially minimum speed to 500 cc. per min. at substantially maximum engine speed, both at wide open throttle. As has been seen, the fuel passage area is maximum when the throttle is wide open. Venturi 18 is chosen of such throat size that the depression on the fuel nozzle 10 located at the throat thereof rises in response to air flow increase resulting from engine speed increase at wide open throttle so as to cause the required fuel to pass through the wide open fuel conduit, and at this time the air bleeding effect is least because the pressure differential on the passage 82 is least.

35 As the venturi is not relied on to induce fuel flow at low fractional loads, as is the case with ordinary carburetor practice it can serve the function of promoting fuel flow at and toward wide open position of the air throttle, and still be large enough not to cause restriction of air flow and reduction of charge density.

If the throttle be closed somewhat from wide open position, as, for instance, to 50°, while this makes substantially no difference in air flow and fuel flow at low engine speeds, there is a material reduction in air flow at the higher speeds, with resulting reduction in need for fuel. At such times, however, the intake depression is higher, but the air bleed passage 82 is more effective in reducing the pressure reduction across fuel valve seat 42, the fuel flow being correspondingly decreased, and the requirements for economical operation satisfied. Upon passing to the lower part fractional load operation, the intake depression is further increased by the further closing of the throttle and the fuel passage area correspondingly reduced in consonance with reduction of throttle opening, and this automatic air-bleed compensation becomes increasingly effective.

60 It will be seen that by my invention at the higher intake depressions, for example, at intake depressions above that existing at wide open throttle high speed, I reduce the effects thereof on fuel flow by air bleeding, and at the lower intake depressions augment the fuel flow inducing effects by air flow through a venturi. The pressure differential on the fuel is thus kept within range to cause, upon fuel passage area adjustment, a flow of fuel in suitable ratio to the air throughout the speed range at each of the throttle positions. At partly open throttle positions the air bleed is more effective for reducing the pressure differential on the fuel throughout the speed range at each of such throttle openings, the air bleeding effect increas-

ing with speed increase and consequent intake depression increase, more rapidly than the fuel flow increases. For maximum throttle opening the air bleeding orifice 86 is adjusted in area to cause economical fuel flow at maximum speeds, 5 neutralizing the tendency of the venturi at such high speeds to cause excessive fuel flow. At minimum speed full load, as above described, the primary air passage 82 closes to render the entire available pressure reduction effective for 10 inducing fuel flow.

Fuel for idling

I preferably supply the fuel for idling entirely independently of the main fuel supplied at other stages of operation, i. e. without being affected by variations in flow of main fuel, and at a relatively constant minimum rate notwithstanding variations or fluctuations of intake depression at or near idling operation. To obtain such result 15 I lift fuel in a solid liquid state through duct 100 from the constant level float chamber 34 into a horizontal chamber or passage section 102 having a relatively weak pressure reduction therein obtained by venting one end of the chamber 20 below the top thereof to the intake through the highly constricted orifice 76 and by venting the other end of the chamber 102 at substantially the same level to the atmosphere through orifice 104 opening into the top of the bowl 34. The 25 pressure reduction developed in chamber 102 attains a value, which is relatively constant, sufficient to lift the fuel into the chamber at the high intake depressions prevailing at or near idling operation so that the idling fuel is available at such stage of operation.

The fuel thus lifted forms a fuel level in chamber 102 without entirely filling the same, thereby preventing vapor locking, which is subjected to the turbulent effect of the air passing through orifice 104, and sweeping over the fuel or there-through to form, apparently, a compressible suspension of fuel in air. The resulting suspension or mixture is squeezed through the highly constricted orifice 76 for delivery through passage 40 30 45 52 and 26 into the intake beyond the throttle. The fixed orifice 76 serves to meter the fuel component therethrough at a substantially constant rate, the mixture being wire drawn, in effect, and issuing through the orifice 76 as 50 a fine stream of atomized fuel particles.

Air bleed opening 104 is preferably somewhat larger than the metering jet opening 76, as, for example in one type of engine the opening 76 was .014" in diameter and opening 104 was .022" in diameter. Satisfactory operation has been obtained with air bleed opening 104 of the order of .020" to .024" in diameter and with a metering orifice 76 of the order of .013" to .015" in diameter.

As already stated, the air bleed passage 82 is open to the atmosphere during idling so that the depression on the metering idling jet 76 which discharges into passage 52 is less than the depression at the fuel nozzle 10, thus enabling the use of a jet size at 76 which is not so excessively small as otherwise would be required, and avoiding frictional effects and irregular flow. In the form of the invention disclosed the idling charge passing jet 76 is carried by the air in passages 70 52 and 26 and discharged through the nozzle 10, the fuel for idling, in effect, being bypassed around the metering orifice 42. With the metering of idling fuel in the form of air-fuel mixture through the jet 76 with openings 76 and

104 of about the sizes above named I find that the idling fuel flow remains substantially constant, giving very smooth and steady idling that does not surge materially even with considerable fluctuation in intake depression.

5 The idling fuel passage 100 and orifices 76 and 104 remain open at all times, but, inasmuch as the idling jet 76 is above the fuel level, and chamber 102 is vented at 104, the fuel quantity 10 supplied at 76 is substantially negligible except at idling and during blending into low fractional load operation, the idling fuel supplied being sufficient to wet the manifold to facilitate passage of the engine from idling into load or speed 15 operation. The contour of the cam edge 72 for controlling the first opening of valve 50 is such as to supply at 42 only the fuel required in addition to that already available at 76, so that there is secured from idling a smooth transition 20 or "take-out" into fractional load operation.

In order to prevent the chamber 102 from flooding and causing flow of solid liquid fuel into the passage 52, the lower end of the passage 100 25 is provided with a relatively restricted metering orifice 106 which chokes off the fuel flow sufficiently to maintain a fuel level in the chamber 102 which under all conditions of engine idling operation remains below the air bleed opening 30 104, this being conducive to the supplying of fuel more uniformly at engine idling. With the orifices 76 and 104 of about the diameters of the order above described, a satisfactory diameter for the orifice 106 has been found to be 35 about .020".

If the air bleed orifice 104 were located above the center of the fuel exit orifice 76, the amount of fuel discharged through 76 would be greater, and if the same were located below orifice 76 40 fuel flow through 76 would be less. Therefore, to effect consistent fuel control, it is necessary to have the idling air bleed 104 on a center line of the exit orifice 76. Without the use of the constricted metering orifice 106, at times erratic 45 fuel metering would occur, as for example, if the engine is accelerating and the throttle is suddenly closed immediately thereafter, the resulting high depression would cause chamber 102 to flood above its normal level, producing a 50 short circuit of the air bleed 104, causing an unduly rich idling condition. With the use of orifice 106 it is possible to maintain a consistent, uniform idle under conditions for good engine 55 operation, the metering orifice 106 preventing, because of its limited capacity to allow fuel flow therethrough, sudden changes in fuel level in the idling chamber.

In the present invention the bleed openings 86 and 104 are vented to atmosphere within the 60 float chamber 34 itself which in turn is vented to the atmosphere through an opening 108 through a saddle portion 110 forming a continuation of the intake air passage 12. The portion 110 is adapted to support an air cleaner 65 112, preferably combined with sound deadening means, which is secured in place by means of the band 114 and bolts 116. The air supplied through opening 108 is thus thoroughly filtered 70 to prevent dust and dirt from clogging up the restricted air bleed orifices.

The air throttle 16 is actuated by the compound leverage system 118, shown at Figs. 3, 5, and 6, adapted for plural actuation from the driver's seat in a well known manner.

75 The fuel pump 64 is used as an effective means

for starting the engine initially. Upon suddenly opening the throttle 16 the fuel content in the well 46 is discharged under pressure through orifice 42 into passages 52 and 82 for delivery upon acceleration into the main nozzle 10 to supply 5 additional fuel for acceleration, overcoming or compensating for the inertia lag in the main fuel flow which occurs when the throttle is thus opened to increase the speed and the intake depression falls momentarily to practically atmospheric pressure. This prevents momentary hesitation of the engine.

In the present invention, I dispense with inter-connecting mechanisms for the control of the movement of the metering pin 50, thereby preventing back lash, distortion and the like, detrimental to precise metering.

By my invention, the pressure differential on the fuel and the fuel orifice variation are co-ordinated so that the fuel is supplied smoothly 20 in suitable ratio to the air substantially throughout the range of operation of the engine without being impeded by frictional effects, notwithstanding that the intake depression varies at times in inverse relation to the fuel requirements, and 25 at other times, while varying directly with fuel requirements, tends to cause either too much fuel flow or not enough. With my system of fuel control the pressure reduction beyond the throttle is made available for the discharge of the fuel 30 directly thereinto so that the fuel, by discharge into a region of reduced pressure, is more easily vaporized, and the same may be discharged directly into contact with heated surfaces without being impeded by the throttle.

35 Fuel atomization and vaporization are also assisted by the bleeding action and by discharge of air centrally through the annular stream of emulsified fuel, so that the fuel assumes under the action of the several vaporizing influences, 40 a thoroughly homogeneous state in suspension in the air.

Having thus described my invention, what I claim and desire to secure by Letters Patent is:

1. In apparatus for supplying and proportioning charges for internal combustion engines comprising a member having an intake passage, and including a depending portion having a fuel passage into the intake passage, a float chamber disposed about and receiving said depending portion, a throttle having a cam portion in said intake passage above said depending portion, and a valvular member in said depending portion for controlling the fuel passage and terminating in said intake passage in engagement with said cam portion to be actuated thereby.

2. In apparatus for supplying and proportioning charges for internal combustion engines comprising a member having an intake passage and including a depending portion having a fuel passage and an accelerating well into the intake passage, a float chamber disposed about and receiving said depending portion, a throttle disposed within said intake passage above said depending portion and including a portion having a cam edge of predetermined contour, a valve for controlling the fuel flow having a bearing in said depending portion and projecting above said depending portion to engage said cam edge, and a plunger working in said well and having a stem portion projecting above said depending portion and connected to said cam portion.

3. In apparatus for supplying and proportioning charges for internal combustion engines comprising an intake, an air controlling means for 75

controlling the air supply to regulate the development of power through the various parts of engine operation, said means carrying a cam having a contour corresponding to a predetermined fuel curve, means including a metering orifice for conducting fuel into the intake at the engine side of said air controlling means, means for introducing primary air into the fuel conducting means at the discharge side of said metering orifice to modify the pressure difference on the orifice relative to the intake depression available, and valvular fuel controlling means having an end thereof engaging said cam and actuated thereby to give at each air control position an orifice area co-ordinated with said means for introducing primary air for allowing a fuel flow, in response to the adjusted pressure differential effective thereon, which is in suitable ratio to the air supplied substantially throughout the pressure differential range.

4. The herein described process of supplying charges for internal combustion engines and proportioning the air and fuel, comprising controlling the passage of air to the engine cylinders for regulating the power production throughout the range of engine operation, introducing fuel through a metering orifice into the air at the engine side of the air controlling means subject to the pressure reduction at the point of fuel introduction while introducing primary air into the fuel line over said metering orifice for reducing the pressure differential thereon, and controlling the metering orifice to produce at each orifice control position a metering orifice of concentrated area coordinated with the attenuated pressure differential on the orifice to reduce frictional coefficients while allowing a fuel flow in suitable ratio to the air.

5. The herein described process of supplying charges for internal combustion engines and proportioning the air and fuel, comprising controlling the passage of air to the engine cylinders for regulating the power production throughout the range of engine operation, conducting fuel through a metering orifice into the air at the engine side of the air control in the region of intake depression while introducing air into the fuel over said metering orifice for reducing the pressure differential thereon, and producing for each of the air control positions a metering orifice of concentrated area coordinated with the reduced pressure differential on the orifice to reduce frictional coefficients while allowing a fuel flow, in response to the pressure differential on the orifice, in suitable ratio to the air supplied.

6. In apparatus for supplying and proportioning charges for internal combustion engines comprising an intake conduit, air controlling means therein for regulating the power production throughout the range of engine operation, means for supplying fuel to the intake conduit at the engine side of the air controlling means, including a metering orifice, means for introducing air into the fuel supplying means at the discharge side of said metering orifice to reduce the pressure differential thereon, and a valve operated automatically and coacting with said metering orifice to form a concentrated orifice opening, the concentrated orifice area and the reduced pressure differential on the orifice at each valve position being coordinated to minimize orifice frictional coefficients while allowing fuel flow in suitable ratio to the air supplied.

7. In apparatus for supplying and proportioning charges for internal combustion engines com-

prising an intake conduit, an air throttle therein for regulating the power production throughout the range of engine operation, means for supplying fuel to the intake conduit at the engine side of the throttle, including a metering orifice, means for introducing air into the fuel supplying means at the discharge side of said metering orifice to reduce the pressure differential thereon, a cam actuated by the air throttle and having a contour corresponding to a predetermined fuel curve, and a valve operated by said cam and coacting with said metering orifice to form a concentrated orifice opening, the concentrated orifice area and the reduced pressure differential on the orifice being coordinated at each throttle position to reduce orifice frictional coefficients, while allowing a fuel flow in suitable ratio to the air.

8. In apparatus for supplying and proportioning charges for internal combustion engines comprising an intake conduit, an air throttle therein for regulating the power production throughout the range of engine operation, means including a float chamber for supplying fuel to the intake conduit at the engine side of the air controlling means, and including a submerged metering orifice, means for introducing air into the fuel supplying means below the fuel level at the discharge side of said metering orifice to reduce the pressure differential thereon, and a valve operated by the throttle in accordance with a predetermined fuel curve and coacting with said metering orifice to form a concentrated orifice opening, the concentrated orifice area and the reduced pressure differential on the orifice being coordinated at each throttle position to reduce orifice frictional coefficients and cause a fuel flow in suitable ratio to the air supplied.

9. In apparatus for supplying and proportioning charges for internal combustion engines, comprising an intake, a pivoted throttle therein for regulating the power production throughout the range of engine operation, means for supplying fuel into the intake at the engine side of the throttle including a metering orifice, means for introducing primary air into the fuel supplying means at the discharge side of said orifice to reduce the pressure difference thereon, a member attached to said throttle for pivotal movement therewith and having a cam edge of a predetermined contour, and a spring controlled valve coacting at one end with said orifice and retained at the other end by said spring in engagement with said cam edge, said valve being actuated by said cam edge to provide an orifice area at each throttle position coordinated with the attenuated pressure difference thereon to produce the desired fuel flow.

10. In apparatus for supplying and proportioning charges for internal combustion engines comprising an intake including an entrance passage portion having a depending part, a pivoted throttle in said entrance passage portion for regulating the power production throughout the range of engine operation, a float chamber receiving said depending part, means including a metering orifice in said depending part for conducting fuel into the intake at the engine side of the throttle, means in said depending part for introducing air into said fuel conducting means at the discharge side of said metering orifice for reducing the pressure difference thereon, a member attached to said throttle for pivotal movement therewith and having a cam edge of a contour corresponding to a predetermined fuel

curve, and a spring controlled valve slidably disposed in said depending part for controlling said metering orifice, and retained at one end by said spring in engagement with said cam edge to be moved thereby.

11. In apparatus for supplying and proportioning charges for internal combustion engines comprising an intake having an entrance passage portion, a throttle pivotally mounted in said entrance portion, a part at the exterior of said entrance portion having a fuel passage therein communicating with the intake at the engine side of the throttle, and including a metering orifice having the axis thereof substantially aligned with the pivot of said throttle, said exterior part having a passage therein for introducing primary air into said fuel passage at the discharge side of said metering orifice to reduce the pressure difference thereon, a valve slidably disposed in said exterior part for controlling the area of said metering orifice, and a member attached to said throttle for pivotal movement therewith and having a cam edge riding on the inner end of said valve to move the same, said cam edge having a contour coordinating the area of the orifice at each throttle position with the attenuated pressure difference on the orifice to produce a fuel flow in accordance with a predetermined fuel curve, the coordination being such as to minimize orifice frictional coefficients.

12. In apparatus for supplying and proportioning charges for internal combustion engines comprising an intake having a horizontal entrance portion, a throttle pivotally mounted in said entrance portion, a depending part at the exterior of said entrance portion having a fuel passage therein communicating with the intake at the engine side of the throttle, and including a metering orifice having the axis thereof substantially aligned with the pivot of said throttle, said depending part having a passage therein for introducing primary air into the fuel passage at the discharge side of said metering orifice to reduce the pressure difference thereon, a float chamber receiving said depending part and submerging said metering orifice, a spring controlled valve slidably disposed in said depending part for controlling the area of said metering orifice, and a member attached to said throttle for pivotal movement therewith and having a cam edge riding on the inner end of said valve to move the same against the tension of said spring, said cam edge having a contour coordinating the area of the orifice at each throttle position with the attenuated pressure difference on the orifice to produce a fuel flow in suitable ratio to the air supplied, the coordination being such as to minimize orifice frictional coefficients.

13. In apparatus for supplying and proportioning charges for internal combustion engines comprising a member having an intake passage and including a depending portion having a fuel passage and an accelerating well therein for supplying fuel to the intake passage, a float chamber disposed about said depending portion, a throttle pivotally disposed in said intake passage above said depending portion, a member attached to said throttle for pivotal movement therewith and having a cam edge of predetermined contour, a valve member slidably disposed in said depending portion for controlling the fuel passage and retained at one end in engagement with said cam edge, and a plunger in said well having a stem projecting above said depending portion and co-

acting with said cam member to be actuated thereby.

14. Process of supplying charges for internal combustion engines, comprising controlling the main air supply to regulate the power output throughout the range of engine operation, introducing primary air into the intake at the engine side of the point of main air control together with fuel introduced into the primary air through a metering orifice subjected to an attenuated pressure differential, and at low depression causing the fuel to close off the admission of primary air hydrostatically to lessen the attenuation of pressure differential effective in producing fuel flow, 10

15. Process in accordance with claim 14 in 15 which there is produced for each throttle position a predetermined orifice area coordinated with the pressure differential effective thereon to give a desired fuel flow at various speeds.

16. Process in accordance with claim 14 in 20 which the fuel orifice is submerged in a constant level source of fuel supply.

17. Process of supplying charges for internal combustion engines, comprising controlling the main air supply to regulate the power output 25 throughout the range of engine operation, delivering primary air into the intake at the engine side of the point of main air control together with fuel introduced into the primary air through a submerged metering orifice subject to an attenuated 30 variable pressure differential produced by the introduction of primary air over the metering orifice, producing for each throttle position a predetermined orifice area to supply the fuel in suitable ratio to the air, the attenuation in pressure 35 differential produced by the primary air being made to approach a maximum to allow the use of metering orifice areas having frictional coefficients approaching the minimum, and at low 40 depressions closing off the primary air by the fuel hydrostatically to effect fuel delivery through the metering orifice under a greater pressure differential.

18. In apparatus for supplying and proportioning charges for internal combustion engines comprising an intake having a throttle therein for regulating the power production throughout the range of engine operation, a passage for conducting primary air into the intake at the engine side of the throttle by the action of the intake depression, a float chamber having a fuel metering orifice therefrom into the primary air passage, said metering orifice and the inlet to said primary air passage being coordinated in area to control the fuel flow so as to compensate for intake depression, said float chamber and said primary air passage being so related that the fuel closes off the supply of primary air at low depression in the intake, 50

19. In apparatus for supplying and proportioning charges for internal combustion engines comprising an intake having an air throttle therein for regulating the power production throughout the range of engine operation, and a passage for conducting primary air into said intake at the engine side of said throttle by the action of intake depression, a float chamber having a submerged 60 metering orifice therefrom to the primary air passage, said metering orifice and the inlet to said primary air passage being coordinated in area to compensate for the intake depression at various 65 throttle positions, said passage hydrostatically leading with fuel at low depression for closing off the primary air, and means operated adjunctively 70

to throttling for producing a metering orifice of predetermined area.

20. In apparatus for supplying and proportioning charges for internal combustion engines comprising an intake, a throttle therein for regulating the power production throughout the range of engine operation, a float chamber, means partially submerged in the float chamber fuel for conducting primary air into the intake at the engine side of the throttle subject to the intake depression substantially over the range thereof, said submerged portion filling with fuel to close off the primary air at low depression, a fuel metering orifice opening into the submerged portion of said primary air conducting means, and having a variable pressure differential thereon attenuated by the primary air, cam means operated adjunctively to throttling for producing at various throttle positions metering orifice areas coordinated with the pressure differential effective on the orifice for producing desired mixture ratios, said orifice areas being proportional to the amount of primary air admitted for reducing frictional coefficients in the orifice.

21. In apparatus for supplying and proportioning charges for internal combustion engines comprising an intake, a throttle therein for regulating the power production throughout the range of engine operation, a venturi in the intake at the engine side of the throttle, a float chamber, means including a submerged metering orifice for conducting fuel into the intake at a point subject to the fuel flow inducing effect of said venturi and intake depression, means for introducing primary air over said metering orifice to reduce the pressure differential thereon, said last named means being controlled hydrostatically by the fuel to close off the primary air at low depression, and attenuating the venturi effect on fuel flow at high speeds, and cam means operated by the throttle for producing at each throttle position a fuel orifice area coordinated with the attenuated pressure differential on the orifice to minimize orifice frictional coefficients while producing the desired fuel flow.

ARLINGTON MOORE.
